(57) **CLAIM**

The ornamental design for a front part of an engine hood for a tractor, as shown and described.

DESCRIPTION

FIG. 1.1 is a front view of a front part of an engine hood for a tractor;

FIG. 1.2 is a rear view of the front part of an engine hood for a tractor shown in FIG. 1.1;

FIG. 1.3 is a left view of the front part of an engine hood for a tractor shown in FIG. 1.1;

FIG. 1.4 is a top view of the front part of an engine hood for a tractor shown in FIG. 1.1;

FIG. 1.5 is a bottom view of the front part of an engine hood for a tractor shown in FIG. 1.1;

FIG. 1.6 is a perspective view of the front part of an engine hood for a tractor shown in FIG. 1.1;

The broken lines shown in FIGS. 1.2 and 1.5 form no part of the claimed design. FIGS. 1.1, 1.3, 1.4, and 1.6 depict the lens covers as being transparent. Right side views are omitted because the right side views are symmetrical to the left side views.
